UNITED STATES PATENT OFFICE.

FRANK M. PHILLABAUM, OF LAKESIDE, OHIO.

GUARD-RAIL CLAMP.

SPECIFICATION forming part of Letters Patent No. 730,151, dated June 2, 1903.

Application filed April 9, 1903. Serial No. 151,871. (No model.)

To all whom it may concern:

Be it known that I, FRANK M. PHILLABAUM, a citizen of the United States, residing at Lakeside, in the county of Ottawa and State of Ohio, have invented new and useful Improvements 5 in Guard-Rail Clamps, of which the following is a specification.

My invention relates to guard-rail clamps; and the object of the same is to construct a 10 device of this character which will be simple and efficient to secure the guard-rail to the track-rail.

The novel construction employed by me in carrying out my invention is fully described 15 and claimed in this specification, and illustrated in the accompanying drawings, forming a part thereof, in which—

Figure 1 is a plan view of a track with my device attached thereto. Fig. 2 is a detail 20 section of the same.

Like numerals of reference designate like parts in both views of the drawings.

The numeral 1 designates a base-plate which is designed to extend beneath the track-rail 25 and guard-rail 3. The ends of the plate 1 are turned up at right angles to form toes 4, which serve as footings for curved braces 5, the lower ends or feet of which are plane and rest on the base 1 and the upper ends or 30 heads are curved to adapt them to engage and fit snugly against the outer sides of the webs 6 and the outer flanges 7 of the rails 2 and 3. The braces 5 have apertures 8 formed in their feet, which apertures regis- 35 ter with apertures 9 in the base 1 to accommo- date bolts 10 fitted therein. Apertures 11 traverse the heads of the braces and register with apertures 12 in the rails 2 and 3. A cross-bolt 13 passes through the apertures 11 40 and 12 and through a longitudinal aperture 14 in a filler-block 15, which is rounded off

on its ends 15^a to fit snugly against the webs 6 of the rails 2 and 3. The inner flanges 17 of the rails 2 and 3 abut and a portion of one or both of these flanges may be trimmed off or 45 rolled down to decrease the interval between the heads of the rails.

I do not wish to be limited as to details of construction, as these may be modified in many particulars without departing from the 50 spirit of my invention.

Having thus described my invention, what I claim as new, and desire to secure by Letters Patent, is—

1. In a guard-rail clamp, the combination 55 of a base-plate having upturned toes formed on the ends thereof, braces footed on said base abutting said toes and bearing against the outer sides of the track and guard rails, a filler-block mounted intermediate said rails, a cross-bolt passing through apertures in said braces, said rails and said filler, and bolts passing through said base-plate and said braces, substantially as described.

2. In a guard-rail clamp, the combination 65 of a base-plate designed to pass beneath the track and guard rails and project beyond the sides of the same, braces footed on said base and headed on the outer sides of the webs of said rails, a longitudinally-apertured filler-block engaging the inner sides of said webs, and a cross-bolt passing through registering 70 apertures in said braces, said webs and the aperture in said filler-block, substantially as described.

In testimony whereof I have hereunto set my hand in presence of two subscribing witnesses.

FRANK M. PHILLABAUM.
